UNITED STATES PATENT OFFICE.

FREDERIC A. LANE, OF NEW HAVEN, CONNECTICUT, ASSIGNOR TO THE
NEW HAVEN CLOCK COMPANY, OF SAME PLACE.

CLOCK-STRIKING.

SPECIFICATION forming part of Letters Patent No. 313,344, dated March 3, 1885.

Application filed November 24, 1884. (No model.)

To all whom it may concern:

Be it known that I, FRED. A. LANE, of New Haven, in the county of New Haven and State of Connecticut, have invented a new Improvement 5 in Clock-Movements; and I do hereby declare the following, when taken in connection with accompanying drawings and the letters of reference marked thereon, to be a full, clear, and exact description of the same, and which 10 said drawings constitute part of this specification, and represent, in—

Figure 1, a front view, the front plate removed to show the mechanism, the stud and three-armed lever represented in their proper 15 position, as if the front plate to which they are attached were present, a part of the arm *i* of the lever broken away to illustrate parts in rear of it; Fig. 2, a top view, portions of the train removed to illustrate the arrangement 20 and operation of the three-armed lever; Fig. 3, the three-armed lever and its immediate connections detached and enlarged; Fig. 4, a perspective view of the end of the lever *e*.

This invention relates to an improvement 25 in that part of a clock-movement by which the striking is produced, and particularly to the style of movement in which the movement is of circular form, the train arranged between two plates, and commonly called a "French" 30 movement. In this class of movement the strike-wheel and the immediately-connecting levers are arranged outside the front plate.

The object of my invention is to bring the 35 entire strike mechanism between the plates, and without increasing the space occupied by this part of the movement; and it consists, principally, in a three-armed lever hung upon a pivot on one plate, one arm extending toward the center or hour shaft and in the path 40 of a cam on said shaft, whereby said arm will be turned by said cam at a predetermined time; a second arm arranged to turn the catch from the strike-wheel and release the train during the first part of the said movement of 45 the first arm; a third arm in the path of a stop on one of the shafts back of the fly, whereby, after the release of the strike-wheel, the movement of the train will be arrested to produce the warning; then as the first arm 50 capes from the cam of the hour-shaft the warning-shaft will be released and the movement

permitted to run to produce the strike, and as more fully hereinafter described.

A represents the back plate, and B the front plate, of the movement; C, the center or hour 55 shaft, which receives its rotation from the time part of the movement. The train which imparts this movement is not shown in the illustration, such train being common and well known.

D is the strike-wheel, arranged on the main-shaft E; F, the strike-finger, which extends from a rock-shaft, G, and from the same shaft an arm, *a*, extends up and terminates in a hook or shoulder, *b*, in the path of a stud, *d*, 65 on the wheel H, which is the second wheel back of the fly I. The strike-finger F and the end *b* of the arm are arranged in the usual relation to the stud *d*, and so that when the finger falls into a notch on the strike-wheel 70 *D*, the shoulder or end *b* of the arm *a* will come into the path of the stud *d* on the wheel H, and thereby arrest the train. This is a common and well-known mechanism.

On a stud, L, extending inward from the front 75 plate, a three-armed lever is arranged. The first arm, *e*, extends toward the center shaft. On the upper side or back of this arm a spring-arm, *f*, is arranged. As here represented, this is a wire extending from the stud, and at 80 the end of the arm *e* passes through a notch, *g*, and so as to project beyond the end of the arm toward the center shaft. On the center shaft is the usual cam, *h*, and which, as the shaft rotates under the action of the time- 85 movement, will strike the projecting spring *f*, and thereby lift the arm, as indicated in Fig. 3, broken lines indicating the normal condition of that arm. The object of the spring will be hereinafter more fully explained. The 90 second arm, *i*, of the three-armed lever extends from the hub in nearly the opposite direction to the arm *e*, and stands over an arm, *l*, projecting upward and inward from the shaft G, and so that as the arm *e* is raised under the 95 action of the cam *h* the cam *i* will be depressed and turn the shaft G to take the strike-finger F out from the notch in the strike-wheel *D*, and at the same time turn the shoulder *b* of the arm *a* from its connection with the stud *d* on the wheel H, which 100 movement liberates the wheel H and permits

the train to proceed under the action of the spring. The third arm, *m*, extends upward from the hub, its end standing near the shaft of the second wheel, *M*. From the shaft of the wheel *M* is a projecting finger, *n*, which in the normal condition of the movement stands back or away from the end of the arm *m* of the three-armed lever, and as seen in Fig. 1. At the time the cam acts to turn the arm *e*, as before described, into the position seen in Fig. 3, and so as to release the train, the arm *m* is thrown toward the shaft of the second wheel, *M*, and into the path of the finger *n*, and so that as the train advances the finger *n* will come into contact with the end of the arm *m*, as seen in Fig. 3, and thus the train will be arrested after a slight movement. This movement is what is commonly called the "warning," and the train will be held in that condition until the center shaft revolves so far as to take the cam *h* from engagement with the arm *e*, as indicated in broken lines in Fig. 3, at which time the three-armed lever is released, and when so released a spring, *r*, (here represented as a wire spring extending from the stud *L*, and arranged to bear upward beneath the arm *i*,) will return the three-armed lever to its normal position, where it rests upon a stud, *s*, projecting inward from the plate of the case, thereby releasing the finger *n*, as well as the strike finger; then the strike-movement proceeds in the usual manner, and until the finger shall fall into the first notch, when the train will be stopped by the engagement of the end *b* with the stud *d* on the wheel *H*, in the usual manner.

By this arrangement of the three armed lever inside the plate I am enabled to bring the entire mechanism of the strike-movement between the two plates. The arm *f* is a spring-arm, the tendency of the spring being upward against the bottom of the notch *g*; but it is free for downward movement. The object of this arrangement is that should the pointers be turned backward—that is, in the direction opposite to that indicated by the arrow, Fig. 3—the cam will strike the end of the spring and turn that spring downward until the cam shall escape therefrom, then the spring will return to its place in the notch. This arrangement therefore permits the pointer to be turned backward without possible interference with the strike mechanism. In some cases the warning may not be required. In such cases the arm *m*, as well as the finger *n* on the second wheel, may be omitted. I therefore do not wish to limit my invention to the necessary employment of the third arm *m*.

60 I have represented the strike-wheel and the center shaft as arranged for hour strikes; but

if intermediate strikes are required the usual arrangement of cams on the center shaft and the construction of strike-wheel corresponding to such intermediate strike will be provided.

If the provision for the backward movement of the pointers is not desirable, then the arm *e* may extend into the path of the cam *h*, as indicated in broken lines, Fig. 3, and the spring *f* be omitted.

I claim—

1. The combination of the strike-wheel *D*, the strike-finger *F*, arm *a*, the stop-stud *d*, the hour-shaft, cam *h* thereon, and a lever arranged upon a stud between the hour and strike-finger shafts, one arm, *e*, extending toward the hour-shaft and into the path of the cam *h* thereon, the other over an arm or projection, *l*, from the shaft of the strike-finger, substantially as described.

2. The combination of the strike-wheel *D*, strike-finger *F*, arm *a*, extending from the strike-finger shaft and into the path of the stud *d* on the wheel *H*, the hour-shaft provided with a cam, *h*, and a lever arranged between the hour-shaft and the shaft of the strike-finger, one arm, *e*, of said shaft extending toward the hour-shaft and carrying a spring, *f*, which projects from the arm into the path of the cam *h*, the said spring arranged to engage the arm in the forward movement of the cam *h*, but free from the arm in the reverse movement of the cam, the second arm, *i*, of said lever extending over an arm, *l*, projecting from the strike-finger shaft, substantially as described.

3. The combination of the strike-wheel *D*, strike-finger *F*, arm *a*, extending from the strike-finger shaft into the path of the stud *d* on the wheel *H*, the hour-shaft provided with a cam, *h*, and a three-armed lever arranged upon a stud projecting inward from the plate of the movement, one of said arms extending toward the hour-wheel and into the path of the cam *h* thereon, the second of said arms extending over a projection, *l*, from the shaft of the strike-finger, the third arm extending toward one of the shafts in the train, near the fly, the said one shaft provided with a finger, *n*, substantially as described, and whereby under the movement of the said three-armed lever, produced by the rotation of the hour-shaft, the count-wheel will be first released by the second arm and the train immediately arrested by said third arm engaging the said finger *n*.

FREDERIC A. LANE.
